Letters Patent August 6. 1834.

The Schedule referred to in these Letters Patent and making part of the same containing a description in the words of the said Joel Woodell him self of his improvement in hammering iron by a machine constructed to supply the place of a common hand as a striker.

To all to whom these presents shall come. Know Ye that I Joel Woodell of Jackson in the County of Madison and State of Tennessee Blacksmith have invented and constructed a new and useful improvement in the art of hammering iron on the anvil by a machine to supply the place of a striker to a common Hodge hammer. Called by the inventor the improved Blacksmiths striker. And the following is a full and perfect description of the plan, combination and operation of said machine.

1st A ground frame composed of four sills ~~timbered~~ and morticed to connect them in nearly a square. The longest or side sills about three feet and one half in length. The shortest or end sills about two feet six inches. All of them from six to nine inches square so as to give strength and weight.

2nd Two upright posts ~~timbered~~ into the sills flush with the outside but so far from the ends as to occupy a station about one foot six inches apart. The projecting ends of the sills will keep the frame steady. The post and the ends near the anvil about 3 inches square and 8 feet 6 inches high. The arms or two back posts about the same size but 3 feet four inches high. The upright posts, arms and cap can be placed on the hindmost upright having also to those in front. These braces can be placed according to the fancy of the builder.

3rd A cylinder about 4 inches diameter to occupy a horizontal position between the upright posts near the anvil. The right hand end of which is supplied by a gadgeon passing through the post and turned into a crank which turns with the hand to turn the end of the gadgeon when it comes another point regard can be had to it by a frame set on the upright post. The length of the crank

2071

from its centre is about six inches. The other end of the cylinder is supported by a guide on the left-hand post. A another cylinder resting on guides also placed horizontally, but between the back upright posts. This cylinder is about 5 or 6 inches diameter swelled at the part of it where the hammer shelve passes through it.

5th A Hinge Hammer on a hub about four feet long set into the last described cylinder near the left-hand end of it. This hub is made to move round upon a journal so as to move the head or face of the hammer to the anvil. A small iron bar set into the hub at the cylinder moves it round and by means of a metallic plate placed on the cylinder holds the hammer to its position a small spring holds the bar in the notch it is wanted to occupy.

6th A chain connected to the last mentioned cylinder at the inside side by a staple & thence brought up with and carried forward to the next upright cylinder over it also and by a hook fastened at the bottom on and on side by the hook the chain can be tightened so as to keep the working power connect and prevent slipping.

7th a pad or chain connecting with the anvil and extending down to near the ground as fastened to a box. This box is of wood and is placed parallel with the longest side. It is about four feet long fastened by a post at the end remote from the anvil the other end to move up and down as a support of a handle which crops at right angles & being in front of the anvil block has its left hand end of it in a position to receive the foot of the anvil the right hand end is fastened by a post like the last.

8th 4 Springs 2 crooping between the upright posts, the ends let into them one of each of them under each cylinder. The third is a topmost spring the end near the anvil block set upon the spring between the front posts passing under the spring between back posts and its centre and is connected by a short chain to the last spring which is set into the cylinder which holds the hammer. The springs are adjusted so as to keep the hammer at its elevation, in which the stroke is directed. A spiral spring of metal may be used instead of the three first springs by fastening

fastening its lower end to part of the frame and the upper end to the end of the spring which is set into the hammer cylinder if the four springs are made all of them may be of wood or metal tho' wood is esteemed the best and cheapest much depends upon the springs their strength and proper adjustment over the lever and cradle frame above described should in some degree be flexible

9th A spring or small rabbit is placed over the hammer which is set into the cap or cap bar on the back of foot. This rabbit keeps the hammer from being thrown too high. The motion in the whole is given by the treadle which operating upon the lever the rod or crank cylinder by means of the connecting chain brings down the Hammer with a force increased by the motion of the foot. The spring twisting the hammer. The whole forming a very striking Blacksmiths aid.

In testimony that the foregoing are my specifications of my invention as above set forth illustrated and described I have this day of May 1834
